UNITED STATES PATENT OFFICE

108,439

DESIGN FOR A GRILL

George A. Hamilton, Albany, N. Y.

Application December 8, 1937, Serial No. 73,479

Term of patent 14 years

To all whom it may concern:

Be it known that I, George A. Hamilton, a citizen of the United States, residing at Albany, in the county of Albany and State of New York, have invented a new, original, and ornamental Design for a Grill, of which the following is a specification, reference being had to the accompanying drawing, forming part thereof.

I claim:

The ornamental design for a grill as shown.

GEORGE A. HAMILTON.
